UNITED STATES PATENT OFFICE

2,045,933

ANTIFRICTIONAL BEARING

Claude Mortimer Townsend, Birmingham,
England

Original application January 13, 1932, Serial No. 586,437, now Patent No. 1,970,439, August 14, 1934. Divided and this application December 23, 1933, Serial No. 703,812. In Great Britain January 13, 1931

3 Claims. (Cl. 308—6)

The invention embodied in this application is a part of that described and illustrated in United States Letters Patent No. 1,970,439, issued August 14, 1934, this application being a divisional application of the one of the serial number aforesaid.

According to this invention an anti-frictional bearing for a straight line moving load has the following combination of parts, namely, an enclosing casing, two tables adapted for separate revolution within said casing, anti-frictional means supporting said tables within said casing both as to axial and transverse thrusts, a roller mounted diametrically across said tables 15 one end of said roller being supported upon one table and the other end of said roller being supported upon the other table, and means stationarily positioning said roller in relation to said casing and said tables.

20 The invention also embodies a constructional arrangement in which the roller revolving upon said tables for support is adapted to swivel about the tables to any angle in a plane at right-angles to the axes of the tables.

25 Fig. 1 is a section of one form of the invention.

Fig. 2 is a section of another form of the invention.

Fig. 3 is a diagram showing an application 30 of the bearing Fig. 2.

With reference to Fig. 1 a single cylindrical roller *j* forms a load member for the straight line moving load. This roller *j* is mounted upon two revoluble tables *e*, *e*¹ situated in the same 35 casing *a* and in the same plane, each of the tables *e*, *e*¹, having a different axis of rotation within said casing. The one end of the roller *j* contacts the table *e*, while the other end of said roller contacts the table *e*¹. The ends of the 40 roller are permanently but loosely located within the casing *a* by pivot ends *j*² of said casing *a*. It therefore follows that when the roller *j* is revolved by a straight line moving load the tables *e* and *e*¹ separately revolve at different 45 rates of speed to accommodate the speed of the roller *j*.

The form of the invention Fig. 2 is substantially the same as the form Fig. 1 but the roller *j*¹ forming the load member extends diametrically across the bearing for support. The end *j*³ of this roller contacts the table *e*³ while the end *j*⁴ of this roller contacts the table *e*⁴ and is free of the table *e*³. The two tables *e*³ and *e*⁴ are concentrically mounted so that the roller 50 *j*¹ can swivel about said tables to any angle in

a plane at right-angles to the axes of the two tables.

Fig. 3 shows two bearings or supports Fig. 2 applied obliquely to a base *t* for the purpose of anti-frictionally supporting a V-slide *u*, such as the sliding table of a planing machine, this showing an adaptation of the invention to a machine.

With reference to Fig. 1, a single cylindrical roller *j* forms a load member for the support of a straight line moving load. This roller *j* is 10 mounted on two revoluble tables *e*, *e*¹ situated in the same casing *a* and in the same plane, each table having a different axis of rotation within 15 said casing.

The table *e*, of largest diameter, forms a rigid 20 part of a ring *f* which is anti-frictionally mounted within the casing *a* upon a ring of balls *g* running upon a base ring *h* fixed to said casing, so that this ring *f*, together with the table *e*, as one-piece, is anti-frictionally supported within 25 the casing both as regards axial and transverse thrusts, that is to say, the table, except for revolution, is immovable by the manner in which it is mounted on the ball bearings *g*. The table *e*¹ forms a rigid part of a ring *i* applied by 30 a circle of ball bearings *l* to a base ring *m* rigidly resting upon the bottom of the casing *a* so that this table *e*¹ is both axially and transversely supported concentrically to the part *n*, which 35 extends between the body and lid of the casing. The one end of the roller *j* rests upon the table *e*¹ and the other end of said roller upon the table *e*, and therefore when the said roller revolves about its own axis the tables *e* and *e*¹ revolve independently at different speeds about their 40 particular axes of revolution and upon the respective ball bearings *g* and *l*. The ends of the roller *j* are permanently but loosely located within a housing *o* of the upper part of the casing *a* by 45 pivot ends *j*², carried by said casing *a*, loosely but permanently engaging pivot centers in the ends of the roller, for the purpose of locating the roller only in relation to the tables, but when said roller *j* is revolving from a straight line moving load the pivot ends are clear of it and the whole weight of the load is borne by the 50 two tables *e* and *e*¹.

The form of the invention in Fig. 2 is substantially similar to that shown in Fig. 1. The roller *j*¹ shown in Fig. 2 and forming the load 55 member, extends diametrically across the bearing and is rotatably mounted with reference to the casing *a*¹, while the roller *j* of Fig. 1 is fixedly mounted for rotation on the casing *a*. The end *j*³ of this roller contacts the table *e*³, while 55

the end j_4 of this roller contacts the table e_4 . The two tables e_3 and e_4 concentrically mounted in the casing a_1 instead of eccentrically as in the form of invention shown in Fig. 1, so that 5 the roller j_1 can swivel about the tables to any angle in a plane at right angles to the axes of both tables, but when the roller j_1 is being revolved only about its own axis the tables e_3 and e_4 revolve about their axes. As the diameter 10 j_3 bearing against the table e_3 is less than the diameter j_4 bearing against the table e_4 , the two tables e_3 and e_4 will revolve at different speeds. The table e_3 forms a rigid part of a ring f_1 which 15 is anti-frictionally mounted upon a ring of balls g_1 running upon a ring h_1 . The table e_4 forms a rigid part of a ring i_1 carried by ball bearings l_1 upon a base ring m_1 .

Figure 3 shows an application of bearings to a planing machine comprising a table u and the 20 base t . Figure 3 is an end elevation showing the end of a bed and table of the planing machine. In such case a number of bearings would be applied at distances apart along the bed for the 25 table to rest and work upon with a straight line motion. Even if the two bearings a, j are obliquely disposed in such case, the movement of the V-slide u is still in a straight line upon the base t , the weight of the slide u being equally 30 distributed between the bearings. Even if there should be a slight tendency of an axial thrust upon the load rollers it would be taken care of by the one table in one direction and the other table in the other direction of each of the two 35 bearings.

Having now described my invention, what I

claim and desire to secure by Letters Patent is:—

1. An anti-frictional bearing for a straight line moving load, comprising a casing, two tables adapted to revolve separately within said casing, anti-frictional means supporting said tables within said casing both as to axial and transverse thrusts, and a roller mounted diametrically across said tables, one end of said roller being supported upon one table and the other end of said roller being supported upon the other table. 10

2. An anti-frictional bearing for a straight line moving load, comprising a casing, two eccentrically mounted tables adapted to revolve separately within said casing, anti-frictional means supporting said tables within said casing both 15 as to axial and transverse thrusts, and a roller fixedly mounted for rotation on said casing diametrically across said tables, one end of said roller being supported upon one table and the other end of said roller being supported upon the 20 other table.

3. An anti-frictional bearing for a straight line moving load, comprising a casing, two concentric tables adapted to revolve separately within said casing, anti-frictional means supporting said tables within said casing both as to axial and transverse thrusts, a roller mounted diametrically across said tables, one end of said roller being supported upon one table and the other end of said roller being supported upon 30 the other table, and means connected with said roller for maintaining the operative position thereof in relation to said two tables.
